UNITED STATES PATENT OFFICE

2,461,215

WIRE CLIP COMBINING SCARF AND COAT

Samuel J. Judge, Rochester, N. Y.

Application November 19, 1946, Serial No. 710,752

3 Claims. (Cl. 2—91)

1

Overcoats are usually made with a short strap below the collar of the coat or on the yoke of the coat by which strap the coat can be hung up. A scarf or muffler is frequently worn about the neck in loose aggregation with the overcoat.

The object of this invention is to provide a wire clip that can be used to combine the scarf with the coat to hold the scarf in place on the overcoat and neck while the overcoat is being worn.

Another object of the invention is to provide the scarf with a buttonhole through which the strap on the overcoat can be drawn and interlocked therewith so that the scarf will be positively held in place on the overcoat while it is being worn.

Another object of the invention is to cut the scarf away on a curved recess so that it will more accurately fit the neck when it is held in place on the overcoat with the wire clip which constitutes part of the subject matter of this invention.

Another object of the invention is to make the wire clip with two diverging arms, each of which carries a hook that opens outwardly and is adapted to engage under the strap of the overcoat and on top of the scarf and interlocks with the strap and the scarf to hold the two of them together.

Another object of the invention is to provide the wire clip with an eye in the central portion thereof by which it may be conveniently attached to the scarf and which increases the elasticity of the diverging arms of the clip.

These and other objects of the invention will be illustrated in the drawings, described in the specification and pointed out in the claims at the end thereof.

In the drawings:

Figure 1 is a view of the central part of the scarf with the ends broken away showing the buttonhole in the scarf with the wire clip fastened to the scarf with a strap.

Figure 2 is a plan view of the scarf and clip with an intermediate portion of each end of the scarf sectioned or broken away.

Figure 3 is a plan view of the collar of the overcoat and the scarf interlocked therewith with the wire clip, the wire clip being shown in engagement with the strap of the overcoat, the scarf and collar of the overcoat being broken away at each end thereof.

Figure 4 shows a vertical section of the coat and scarf the section being on the line 4x, 4x of Figure 3.

2

Figure 5 shows a horizontal section, the section being taken on the line 5x, 5x of Figure 3.

Figure 6 shows a modification of a clip shown in the other figures.

5 In the several figures of the drawings, like reference numerals indicate like parts.

Reference numeral 1 indicates the standard collar of an ordinary top coat or an overcoat. 2 indicates a scarf laid on the collar of an overcoat and 3 indicates the strap which is ordinarily provided on coats by which they may be hung up.

In the scarf 2 is formed a buttonhole 4 which buttonhole is present in the scarf shown in Figure 3, but is concealed by the strap 3, which strap 15 is drawn forward through the buttonhole. The strap 3 is fastened at each end to the lower part of the collar or to the yoke of the coat just below the collar, and the part of the strap between the ends is left loose or free from the coat but ordinarily lies close against the coat.

The scarf is cut away at the neck on the lower side as indicated at 5 and the wire clip 6 is fastened to the scarf by a strap 7 as is indicated in Figure 1. This clip 6 is formed on one piece

25 of wire which is bent on itself to form an eye 8 in the central portion of the clip. The two arms 9, 9 of the clip are bent to diverge downwardly at an angle from the eye and at the outer end of each arm a hook 10 is formed each of 30 which hooks open outwardly from the center of the clip. Each arm and its hook is symmetrical with the other arm and is spread outwardly from the eye 8, the one arm and its hook being a duplicate of the other arm, the parts of each arm being arranged in reverse order to the parts of the other arm so as to be symmetrical therewith.

In use this scarf is laid on the overcoat so that the buttonhole 4 of the scarf 2 is over the strap 3 and parallel to it. The strap 3 is then pulled 40 through the buttonhole as is shown in Figures 4 and 5. The two hook-shaped ends 10, 10 are then inserted under the strap and left on top of the scarf as is shown in Figure 3 and 4. This positively fastens the scarf to the overcoat. When 45 the overcoat is put on by the person wearing it, the scarf will be accurately placed with reference to the coat and the neck of the person wearing it so that the ends of the scarf can be brought forward over the shoulders and can be crossed over the chest of the person wearing the coat. If the scarf is cut away as shown at 5 in Figure 3, the scarf will more accurately fit the back of the neck and will not be gathered up or bunched up under the neck of the overcoat. When the coat 50 is removed the scarf will be held in place on the

coat ready to be worn again. By pressing the two ends of the clip together it can be removed from the combined scarf and coat and the scarf and coat can be separated.

I claim:

1. A muffler construction arranged for cooperation with the conventional hanging strap found in the neck band of a top coat comprising an elongated muffler having a buttonhole formed longitudinally therein and located centrally thereof, said muffler being disposed transverse the shoulder portion of a top coat with the hanging strap extended through the buttonhole therein from the rear thereof, and resilient means for engaging said hanging strap in an extended position and in engagement with the muffler button-hole for the purpose described.

2. A muffler construction arranged for cooperation with the conventional hanging strap found in the neckband of a top coat comprising, an elongated muffler having a buttonhole formed longitudinally therein and centrally thereof, said muffler being cut away to form a neck and shoulder space below said buttonhole, a wire clip having an eye centrally thereof and having diverging arms terminating in hook ends, said clip eye having attachment to said muffler below said buttonhole, said muffler disposed transverse the shoulder portion of a top coat with the hanging strap extending through the buttonhole therein, and the hooked ends of said clip arms being inserted under the hanging strap for the purpose of attaching said muffler to the top coat.

3. A muffler construction arranged for cooperation with the conventional hanging strap found in the neckband of a top coat comprising, an

elongated muffler having a buttonhole formed longitudinally therein and located centrally thereof, said buttonhole being of less overall length than the overall loop length of the hanging strap, said muffler being cut away to form a neck and shoulder space below said buttonhole, a resilient wire clip having an eye centrally thereof and arms diverging from said eye, hooked ends terminating each of said diverging clip arms, a looped strap passing through said clip eye and having connection with said muffler below said buttonhole, said muffler disposed transverse the shoulder portion of a top coat with the hanging strap extending forwardly through the button-hole therein, and the clip being moved upwardly to lie on the front of the muffler with the hooked ends of the diverging arms being inserted under the hanging strap to spread the strap beyond the ends of the buttonhole for the purpose of attaching the muffler to the top coat.
